US00D903126S

(12) **United States Design Patent** (10) Patent No.: **US D903,126 S**
(45) Date of Patent: **** Nov. 24, 2020**

(54) **MONITORING DEVICE**

(71) Applicant: **GastroKlenz Inc.**, San Francisco, CA (US)

(72) Inventors: **Gerd Schmieta**, Boston, MA (US); **Eric Hsiang Yu**, San Francisco, CA (US); **Aly R. Elbadry**, San Francisco, CA (US)

(73) Assignee: **GASTROKLENZ INC.**, San Francisco, CA (US)

(**) Term: **15 Years**

(21) Appl. No.: **29/696,317**

(22) Filed: **Jun. 26, 2019**

(51) LOC (12) Cl. **24-01**

(52) U.S. Cl.

USPC **D24/186**; D24/169; D24/108

(58) Field of Classification Search

USPC D24/107, 108, 164, 169, 186, 216; D10/81

CPC A61M 1/28; A61M 1/282; A61M 2205/3306; A61M 2205/3334; A61M 2205/50

(57) **CLAIM**

The ornamental design for a monitoring device, as shown and described.

DESCRIPTION

FIG. 1 is a front left upper perspective view of a monitoring device showing the new design;

FIG. 2 is another front left upper perspective view thereof;

FIG. 3 is a front right upper perspective view thereof;

FIG. 4 is a rear lower right perspective view thereof;

FIG. 5 is a rear lower left perspective view thereof;

FIG. 6 is a front view thereof;

FIG. 7 is a rear view thereof;

FIG. 8 is a right side view thereof;

FIG. 9 is a left side view thereof;

FIG. 10 is a top plan view thereof; and,

FIG. 11 is a bottom plan view thereof.

The broken lines depicting a tube in FIG. 1 represent an environment, and the remaining broken lines illustrate portions of the monitoring device that form no part of the claimed design. The broken lines form no part of the claimed design.

1 Claim, 11 Drawing Sheets
